Des. 235,427

Patented June 17, 1975

235,427

BICYCLE HANGER

Alexander L. Generalis, and Michael C. Roberto, both of
249 S. 10th St., Philadelphia, Pa. 19107

Filed May 11, 1973, Ser. No. 359,215

Term of patent 14 years

Int. Cl. D8—99

U.S. Cl. D12—115

FIG. 5

FIG. 4

FIG. 2

FIG. 3

FIG. 6

FIG. 1 is a perspective view of a bicycle hanger showing our new design, it being understood that the broken lines are for illustrative purposes only.

FIG. 2 is a top plan view thereof.

FIG. 3 is a bottom plan view thereof.

FIG. 4 is a rear elevational view thereof.

FIG. 5 is a front elevational view thereof.

FIG. 6 is a side elevational view, the opposite side being substantially a mirror image thereof.

We claim:

The ornamental design for a bicycle hanger, as shown and described.
